CLAIM

The ornamental design for a disposable container for hospital surgery room discards, as shown and described.

DESCRIPTION

FIG. 1 is a side elevational view of a disposable container for hospital surgery room discards showing my new design, the opposite side elevational view being a mirror image of that shown;

FIG. 2 is a rear elevational view thereof;

FIG. 3 is a front elevational view thereof;

FIG. 4 is a top plan view thereof; and

FIG. 5 is a bottom plan view thereof.

*Fig. 1.**Fig. 2.**Fig. 4.**Fig. 5.**Fig. 3.*
